US00D714989S

(12) **United States Design Patent**
Rowlette, Jr. et al.

(10) **Patent No.:** US D714,989 S
(45) **Date of Patent:** ** Oct. 7, 2014

(54) **LIGHTING MODULE COMPONENT**

(71) Applicant: **Cree, Inc.**, Durham, NC (US)

(72) Inventors: **John R. Rowlette, Jr.**, Raleigh, NC (US); **Jeremy Johnson**, Fuquay Varina, NC (US)

(73) Assignee: **Cree, Inc.**, Durham, NC (US)

(**) Term: **14 Years**

(21) Appl. No.: **29/469,362**

(22) Filed: **Oct. 9, 2013**

Related U.S. Application Data

(62) Division of application No. 29/404,382, filed on Oct. 20, 2011, now Pat. No. Des. 694,456.

(57) **CLAIM**

The ornamental design for lighting module component, as shown and described.

DESCRIPTION

FIG. 1 is a front plan view of a lighting module component according to the new design, wherein the lighting module component is a light source.

FIG. 2 is a first front perspective view of the lighting module component of FIG. 1.

FIG. 3 is a second front perspective view of the lighting module component of FIG. 1.

FIG. 4 is a first rear perspective view of the lighting module component of FIG. 1.

FIG. 5 is a second rear perspective view of the lighting module component of FIG. 1.

FIG. 6 is a rear plan view of the lighting module component of FIG. 1.

FIG. 7 is a first side plan view of the lighting module component of FIG. 1.

FIG. 8 is a second side plan view of the lighting module component of FIG. 1.

FIG. 9 is a third side plan view of the lighting module component of FIG. 1; and,

FIG. 10 is a fourth side plan view of the lighting module component of FIG. 1. The broken lines shown in the drawings depict portions of the lighting module component that form no part of the claimed design.

1 Claim, 3 Drawing Sheets
